DESIGN FOR A CONTAINER FOR PERFUME OR THE LIKE

Bertha H. Ogden, New York, N. Y., assignor to Babs Creations, Inc., New York, N. Y., a corporation of New York

Application February 14, 1940, Serial No. 90,244

Term of patent 3½ years

To all whom it may concern:

Be it known that I, Bertha H. Ogden, a citizen of the United States and a resident of the city of New York (Borough of Manhattan), county and State of New York, have invented a new, original, and ornamental Design for a Container for Perfume or the like, of which the following is a specification, reference being had to the accompanying drawing, forming part thereof, in which—

Figure 1 is a front view, in perspective, of a container for perfume or the like showing my new design; and

Figure 2 is a rear view, in perspective, of the container.

I claim:

The ornamental design for a container for perfume or the like, substantially as shown.

BERTHA H. OGDEN.
